United States Patent Office

Des. 219,909
Patented Feb. 16, 1971

219,909

JAR

Clarke Hambley and Joseph Torres, Westchester County, N.Y., assignors to Chesebrough-Pond's Inc.

Filed Nov. 3, 1969, Ser. No. 19,904

Term of patent 14 years

Int. Cl. D9—01

U.S. Cl. D9—163

FIG. 1.

FIG. 2.

FIG. 3.

FIG. 4.

FIG. 1 is a side elevational view of a jar showing our new design, the opposite side being the same in appearance;

FIG. 2 is an end elevational view, the opposite end being the same in appearance;

FIG. 3 is a top plan view; and
FIG. 4 is a bottom plan view thereof.

We claim:

The ornamental design for a jar, as shown and described.
